UNITED STATES PATENT OFFICE

ARCHYBAL L. GRIFFITH, OF CUSHING, OKLAHOMA

AUTOMATIC FLUID LIFT

Application filed April 30, 1929. Serial No. 359,293.

This invention relates to fluid lifts and is more particularly adapted for connection to the end of the conductor pipes in oil and gas wells, and an object of the invention is to utilize the gas pressure in oil and gas wells for automatically forcing oil or water to the surface of the ground. This device will keep the sand dry at all times by taking very little gas through the tubing, and will conserve the gas by eliminating opening the wells into the air to relieve them of fluid, also preventing coning of water, and keep sand dry at all times.

Further objects of the invention are to provide, in a manner as hereinafter set forth, a device of the character referred to, which is strong, compact and durable, thoroughly reliable in its operation, very simple in its method of assembly and comparatively inexpensive to manufacture and install.

With the foregoing and other objects in view the invention consists in the novel construction, combination and arrangement of parts as will be hereinafter more fully described and illustrated in the accompanying drawings, wherein is disclosed an embodiment of the invention, but it is to be understood that various changes, and modifications may be resorted to, without departing from the spirit of the claims hereunto appended.

In the drawings, wherein like reference characters designate like parts throughout the several views:

Figure 1 is a vertical sectional view through the device, in accordance with this invention.

Figure 2 is a horizontal section taken substantially on the line 2—2 of Figure 1, and

Figure 3 is a horizontal sectional view, taken on line 3—3 of Figure 1 and looking in the direction of the arrows.

Water problems of one kind or another must be dealt with at almost every stage in operating a gas field, and as the field grows older, the trouble caused by water tends to increase both in number and severity. New fields are generally subject to edge water encroachment, together with water coning, shutting off more and more of the gas until the well involved goes entirely to water. As stated above, this device will take very little

gas to operate, and keeps the sand dry at all times.

Referring to the drawings in detail, 5 indicates a hollow cylindrical casing having a closed end 6 and inwardly flared annular shoulders 7 terminating in a reduced internally threaded opening 8 at its upper end. A tubular member 9 having open upper and lower ends 10, 11 respectively is supported in spaced relation to the walls of the casing 5 on tri-furcated brackets 12, 13, adjacent the upper and lower ends of the roof.

Intermediate the upper and lower ends of the tubular member 9 about one-third of the length of the tubular member 5 from the top thereof is rigidly secured between the walls of the casing and tubular member, an imperforate annular ditch 14 which partitions in an air tight manner the space between the tubular walls and the spacing walls.

The latter construction provides for the passage of the gas from the well pocket as will be presently disclosed.

Intermediate the partition disk and the lower end of the tubular member 11, the casing is formed with three pairs of diametrically disposed axially spaced openings 15, 16, and 17, the upper opening 15 of which is spaced below the partition disc 14 and the lower 17 being spaced from the closed bottom end 6 of the casing. Above the partition disc 14 and spaced at quadrants around the spacing walls 5 are a series of aligned openings 18 which extend into the compartment between the casing and tubular member so that the gas from the well pocket may flow into the same upwardly to force the oil to the surface of the ground. The upper end 10 of the tubular member 9 terminates subjacent the threaded opening 18 in the area of the inwardly flared annular shoulder 7. In the operation of the device, the internally threaded reduced end 8 of the outer casing 5 is screwed on the lower end of the conductor pipe which is lowered into the well, whereupon the casing 5 is disposed in the well pocket. The oil enters the casing 5 through the series of openings 15, 16, and 17, and collects in the lower closed end 6 surrounding the lower end 11 of the tubular member 9. It is to

be understood, of course, that the conductor pipe is lowered and the well casing and packing is interposed between the outside of the conductor pipe and the inner walls of the inner casing so as to prevent the escape of gas.

This practice is common in the oil fields and is well known in the art. The imperforate partition disc 14 prevents oil from flowing into the upper compartment of the casing 5 and gas is admitted thereto through the series of openings 18 and flows through the compartment or space between the tubular member 9 and the walls of the casing 5 and through the inwardly flared shoulders 7, thereby creating a suction at this point, while at the same time forcing the oil that has been drawn through into the reduced end 8, upwardly into the conductor pipe (not shown in this drawing). In this manner, the oil is forced to the surface of the ground by the automatic action of the gas in the oil pocket.

Having described my invention, what I claim as new is:

1. A device of the character referred to comprising an outer hollow casing having axially spaced openings intermediate its ends, said casing having a reduced end provided with an internally threaded opening in communication with the interior thereof for connection to an oil conducting pipe, a tubular member supported in spaced relation to the inner walls of the casing and an imperforate partition wall secured to the tubular member and the casing subjacent the highest opening, said tubular member terminating in spaced relation to the opposite ends of said casing.

2. A device of the character referred to comprising an outer hollow casing having axially spaced openings intermediate its ends, said casing having a reduced end provided with an internally threaded opening in communication with the interior thereof for connection to an oil conducting pipe, a tubular member supported in spaced relation to the inner walls of the casing and an imperforate partition wall secured to the tubular member and the casing subjacent the highest opening, said tubular member terminating in spaced relation to the opposite ends of said casing, and above and below the openings.

3. A device of the character referred to comprising an outer hollow casing having axially spaced openings intermediate its ends, said casing having a reduced end provided with an internally threaded opening in communication with the interior thereof for connection to an oil conducting pipe, a tubular member supported in spaced relation to the inner walls of the casing and an imperforate partition wall secured to the tubular member and the casing subjacent the

highest opening, said tubular member terminating in spaced relation to the opposite ends of said casing and above and below the openings, the walls of the casing merging with the threaded opening flared inwardly to provide increased tension at the upper mouth of the tubular member.

4. A device of the class described comprising an outer hollow casing having axially spaced openings intermediate its ends, one end of the casing being opened, means at the outer end of the casing for engaging the same with an oil conducting pipe, a tubular member supported in spaced relation to the inner walls of the casing, and an imperforated partition wall secured to the tubular member and the casing subjacent the upper openings, said tubular member extending above and below the partition wall and terminating in spaced relation to the closed end of the casing.

In testimony whereof I affix my signature.

ARCHYBAL L. GRIFFITH.
